US0D1052257S

(12) **United States Design Patent** (10) **Patent No.:** **US D1,052,257 S**
(45) **Date of Patent:** **** Nov. 26, 2024**

(54) **CAPSULE HOLDER**

(71) Applicant: **Nanjing Langs Electronics Technology Co., Ltd**, Nanjing (CN)

(72) Inventor: **Ke Zhao**, Nanjing (CN)

(73) Assignee: **Nanjing Langs Electronics Technology Co., Ltd**, Nanjing (CN)

(**) Term: **15 Years**

(21) Appl. No.: **29/950,050**

(22) Filed: **Jun. 29, 2024**

(51) LOC (14) Cl. **03-01**

(52) U.S. Cl.

USPC **D3/203.1**

(58) **Field of Classification Search**

USPC D3/201, 203.1–203.4, 313; D24/100,

Primary Examiner — Steven J Czyz

(74) Attorney, Agent, or Firm — Nitin Kaushik

(57) **CLAIM**

The ornamental design for a capsule holder, as shown and described.

DESCRIPTION

FIG. 1 is a front perspective view of a capsule holder, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

1 Claim, 8 Drawing Sheets
